UNITED STATES PATENT OFFICE.

THOMAS H. DUNNE, OF SAN FRANCISCO, CALIFORNIA.

PENCIL.

Application filed October 20, 1926. Serial No. 142,853.

This invention relates to improvements in pencils and more particularly to writing or marking pencils having replaceable leads adapted to be mechanically extended beyond the body of the pencil. Among the objects of this invention are to produce a pencil of this character having the minimum number of parts in combination to produce the desired mechanical effect, with an attractive 10 finish, well balanced, simple in operation and that may be produced at such a low cost that it is adaptable for free distribution for advertising purposes, and as an economical substitute for the conventional wood pencil 15 having fixed leads therein.

This conventional type of pencil having a lead fixed within a wooden body, while low in first cost, is relatively expensive in ultimate consumption, for the reason that the 20 wooden body is cut away to expose the lead or marking element embedded therein, which is wasteful of the lead because more of it is sharpened away than is actually used for writing, in many instances. Further waste 25 is due to the fact that when the pencil becomes too short for comfortable writing it is discarded, often amounting to a waste of over fifty per cent. The low production cost of the present invention provides for the replacement of the leads or marking elements 30 as they are worn away without wasting or destroying the holding element or body of the pencil. The durability of the present structure is sufficient to outwear so many of 35 the type of pencils having fixed leads, that the cost of the mechanical features of the present invention are more than compensated for. Practically the entire length of the lead or writing element is used, and the 40 ultimate quantity that would be consumed within one mechanical holder would represent a large saving, due to the absence of waste of any kind. Other objects and advantages will appear as this description 45 progresses.

In this specification and the annexed drawings the invention is illustrated in the form considered the best, but it is to be understood that it is not limited to such form, because 50 it may be embodied in other forms, and it is also to be understood that in and by the claim following the description it is desired to cover the invention in whatsoever form it may be embodied.

28. In the accompanying one sheet of draw-

ings, Figure 1 is a mechanical pencil constructed in accordance with this invention, the enclosing body being shown in longitudinal section and the mechanical combination of elements assembled therein being shown 60 in full line, better to disclose their form and co-operation. Figure 2 is a plan view from above, looking down into the end of the pencil, with the eraser removed. Figure 3 is a fragmentary detail partially in cross 65 section, illustrating the position of the plunger for ejecting the last stub of lead. Figure 4 is a cross section of a modified form, adapted to tubular metal bodies. For better disclosure the various parts are shown, 70 greatly enlarged, practically twice the normal size.

In detail the construction illustrated in the drawings comprises the tubular shaft or body of the pencil 1, which is preferably 75 made of wood, paper, or any of the well known compositions available for this purpose. This body 1 has a central axial bore 2, throughout its length, the lower or writing end of the body 1 is provided with a 80 sheath 3 tapering to a point and terminating in a central opening, closely fitting the diameter of the lead to be used within the body. This sheath has a parallel portion 4 frictionally held on the end of the body 1, that has a diametrical reduction and is tapered to fit within the sheath so that the body and the sheath will present an externally flush surface. The opposite end of the body is provided with the reduced nipple 5 consisting of a tubular section forced onto a diametrical reduction on the end of the body. The tubular ferrule 6 is forced over the nipple 5 and has the same external diameter 85 as the body portion 1 so that it presents a 90 flush surface therewith, the end of the body 1 being diametrically reduced to accomplish this. With this ferrule 6 placed over the end of the body and the nipple 5, the groove 7 is formed in a swaging machine, which 95 permanently attaches the ferrule 6 to the end of the pencil and the nipple 5; the groove 7 swiveling the parts 5 and 6 together and forcing the nipple 5 into the body of the wood, securely assembling the 100 nipple and ferrule on the end of the body 1. The internal and external diameters of the nipple 5 and the ferrule 6 are such that the ferrule 6 swivels freely on the nipple 5, being capable of a free and complete rota- 110

tion thereon. The ferrule 6 is provided with a knurled portion 8. The act of knurling this portion tends to enlarge the external and internal diameter of the ferrule 6, causing a slight parallel swelling at this point, with an externally roughened surface to provide friction for the fingers in turning the ferrule 6. The upper extremity of the ferrule 6 is provided with the thread grooves 9 to aid in frictionally securing the cylindrical rubber eraser 10 therein.

The mechanical feed comprises the continuous helix or open spiral 11 formed of flat wire or a ribbon like strip of sheet metal. 15 The spaced convolutions of the hollow wire when wound upon a mandrel of the desired size, forms in mechanical effect, a hollow thread or screw, rotatably fitting within the parallel axial bore 2 throughout the body of the pencil. The upper end of this helix terminates in an enlarged head integral therewith, but wound upon a larger mandrel to form in effect a compact expansive head 12.

The traveller 13 for expelling the lead or 25 marking element from the body, comprises a length of wire 13 bent back upon itself at 14 and again bent back upon itself at 15 and terminating against the side of stem 13. The distance between the bends 14 and 15 30 is approximately equal to about two convolutions of the helix 11. This plunger is assembled upon the helix by holding it in one hand while the end 16 of the helix is rotated through the loop formed between the 35 bends 14 and 15, which carries the stem 13 within the helix, leaving the parallel extension 17 outside the helix.

The combination is assembled by grasping the head 12 of the helix and forcing the 40 end 16 into the upper end of the bore 2 through the body of the pencil, the loop 17 of the plunger engaging the longitudinal groove 18 formed throughout the length of the bore 2. The head 12 is then forced into 45 the upper end of the ferrule 6 until it expands within the enlarged knurled portion 8, wherein it is securely held by frictional contact due to the normal expansion of the head 12. The ferrule 6 and the helix 11 50 move as one integral part when the ferrule 6 is rotated on the end of the body 1. After the head 12 is in position within the ferrule the eraser 10 is forced into the end of the ferrule, completing the assembly and the 55 finish of the body of the pencil.

With the plunger in the retracted position as shown in Figure 1, one or more lengths of leads such as 19 and 20 are inserted in the open end of the sheath 3 and 60 are forced upward within the helix 11, within which they snugly fit, yet may longitudinally freely move. It is desirable that this lead 19 fit snugly within the helix 11 so that there will be no lost motion or 65 wobbling of the lead during the act of

writing and to prevent the lead sliding out of the body of the pencil. As the point 19 wears away the body 1 of the pencil is grasped in the right hand and the ferrule 6 turned to the right or clock-wise, which 70 causes the left hand thread of the helix 11, working within the loop of the traveller 17 to force the same outward, the end of the stem 13 impinging against the upper end of the lead 20 forces the same forward, which 75 in turn forces the lead 19 forward, exposing more writing element until all of the leads are consumed. By the time the loop 15 impinges against the tapered side of the sheath 3, the end of the plunger 13 has protruded 80 through the end of the sheath and ejected the last stub of lead, see Figure 3.

To refill the pencil the ferrule 6 is then turned in the reverse or contra-clock-wise direction which again screws the traveller 85 back into the position shown in Figure 1, ready to receive a new charge of lead within the magazine formed by the length of the helix 11. It is desirable to divide the length of lead as shown, since a continuous 90 length of approximately five inches is liable to breakage and is unwieldy for various obvious reasons. A further advantage of the shorter leads within the magazine, is that more than one color may be carried. For 95 instance, the lead 19 might be black or blue and the lead 20, red, or any other contrasted color. It often happens that for checking invoices and other such purposes it is desirable to use a set color marking, perhaps 100 over a period of hours at a time, or during another period, it would be desirable to use another color. Any of the colors within the magazine are available by merely turning the ferrule 6 until the desired color is 105 exposed through the end of the sheath 3, the ejected lead being laid aside for reinsertion.

The body portion 1 being of wood or similar composition, is susceptible to en- 110 ameling, coloring and other treatment, rendering it attractive to the eye and comfortable to the touch. The outer surface may also carrying advertising matter imprinted thereon, making this invention an economical, attractive advertising medium for free 115 distribution.

It is obvious that the body portion 1 may be made of a metal tube, square or polygonal, the loop 17 of the plunger travelling 120 up and down in one of the angles of the tube to prevent it from turning, serving the same function as the groove 2 in the wooden body portion 1, see Figure 4. This modification is particularly adaptable to the use of 125 large marking crayons, wherein it is desirable to keep the cross sectional diameter of the body 1 within comfortable size. The particular advantage of the structure shown in Figure 1 is that, leads of relatively large 130

diameter may be inserted within the conventional diameter of the ordinary wooden pencil, which is approximately five-sixteenths of an inch. This structure also lends itself to the making of pencils of very small diameter for handling small leads for insertion within pocket memorandum books, or purses.

Having thus described this invention what I claim and desire to secure by Letters

10 Patent is:

A mechanical pencil comprising a body having a longitudinal bore with a groove extending laterally therefrom throughout the length of said body; a nipple surrounding the end of said body and attached thereto by a depressed groove; a ferrule surrounding said nipple and engaged to swivel in said groove; a tapered sheath on

the end of said body flush with the outer surface thereof and terminating in an opening co-axial with said bore; a helix within said bore and extending beyond both ends of said body and having an enlarged spiral head expansively and directly engaging within said ferrule and adapted to be driven thereby, the opposite end of said helix extending within said sheath to near said opening therein; and a traveler looped into and driven by said helix and guided in said lateral groove in the body and adapted to advance beyond the end of said sheath a lead held within and by said helix.

In testimony whereof I have hereunto affixed my signature.

THOMAS H. DUNNE.
